C. J. DALLEY.
AUXILIARY WATER TANK.
APPLICATION FILED JULY 17, 1918.

1,300,702.

Patented Apr. 15, 1919.

Dyke & Campfield

UNITED STATES PATENT OFFICE.

CHARLES J. DALLEY, OF NEWARK, NEW JERSEY.

AUXILIARY WATER-TANK.

1,300,702.

Specification of Letters Patent. Patented Apr. 15, 1919.

Application filed July 17, 1918. Serial No. 245,430.

To all whom it may concern:

Be it known that I, CHARLES J. DALLEY, a citizen of the United States, and a resident of Newark, county of Essex, and State of New Jersey, have invented certain new and useful Improvements in Auxiliary Water-Tanks, of which the following is a specification.

My invention relates to an auxiliary water tank adapted to be attached directly to the water intake of water cooled internal combustion motors.

An object of the invention is to provide such a tank of simple construction and which can be readily attached.

Another object of the invention is the provision of a tank of the character referred to which can be directly attached to the water intake of the motor and is firmly and strongly supported thereby, requiring no exterior support.

With the foregoing and related objects in view, my invention consists in the elements and combinations hereinafter referred to and pointed out in my claims.

In the accompanying drawing I have shown a water tank embodying my invention attached directly to a motor of an automobile of the Ford type, but it is to be understood that such showing is only for the purpose of affording a clear understanding of my invention and not for the purpose of limitation.

In said drawing, Figure 1 is a side view with parts broken away, and showing my tank in place and connected to an automobile engine and radiator, and Fig. 2 is an enlarged cross-sectional detail view taken on the line 2-2, Fig. 1 and looking in the direction of the arrows.

Reference character 10 designates an automobile engine and 11 a radiator. 12 is the water outlet pipe from the engine to the radiator, and 13 is a water outlet connection at the bottom of the radiator. As such automobiles are manufactured and put out, they are arranged for "thermo-siphon" circulation and direct pipe connection is made from the radiator outlet 13 to the water intake 14 of the motor, and when a tank in accordance with my invention is utilized, such pipe connection is removed and replaced by the tank and its connections. 15 designates a tank in accordance with the present invention. 5 Such tank may be of any preferred form, but preferably it is fairly high and compara-

tively narrow substantially as shown in the drawing, being preferably constructed of such form in order that it may be conveniently located under the hood of an automobile.

The tank is directly connected to and supported by the motor. The connecting means, as bolts 16, 16, are preferably passed entirely through the tank so as to be conveniently accessible, and a spacing member is provided between the side walls 17, 17 of the tank. Such spacing member may have the form of a casting 18 and may comprise a substantially ring-shaped portion 19 having an opening 20 therein to register with the intake opening 14 of the motor, and a pair of posts or studs 21, 21 having bores 22, 22 to receive the bolts 16, 16. The member 18 is preferably of substantially the outline of the pipe connection flange or facet 23 provided on the motor casting, and the gasket 24, which normally serves for making a tight connection between the ordinary inlet pipe and the inlet 14 may be made use of for giving a tight connection between the tank and the water intake. Means are preferably provided for holding and maintaining the member 18 in place within the tank, and in the form shown the bores 22, 22 are enlarged at their ends for a short distance, as shown at 25, and the material of the tank walls 17, 17 is forced or driven inwardly around the openings for the bolts 16, 16 to enter the enlargements 25 of the bores 22, and in this way the member 18 will be held and remain in its proper place even when the bolts 16, 16 are removed, as will be readily understood.

Means are provided, when necessary, for the passage of operating devices connected with the motor through the tank. As, for example, in the Ford type of engine the throttle operating mechanism passes beneath the water inlet opening, and with a tank adapted for use with such engine, a passage, as 26, for the throttle control device, may be provided through the tank, as, for example, by passing the tubing 27 through properly provided openings in the tank and soldering or otherwise securing it in place therein. The water inlet of the tank is preferably located at the lower side thereof and may be at the lower forward portion as at 28, a comparatively short water inlet neck, such as 29, being preferably provided which may conveniently be

connected, as by a piece of rubber tubing or the like, to the water outlet 13 of the radiator 11. An air vent is preferably provided at the top of the tank to prevent air pocketing when filling the circulating system with water. A screw 30, which may be loosened by unscrewing somewhat to permit air to pass out and tightened after filling to prevent leakage, may be used for this purpose, 10 or various other types of vent may be used. It will be seen that a tank in accordance with my invention is of extremely simple construction, that it can be connected directly to the water inlet of the motor and 15 may be supported by the connecting means, requiring no exterior supporting device, and that no changes in the construction of the engine and radiator are required, all that is necessary being simply to remove the ordinary piping connection from the radiator outlet to the water inlet of the motor and to replace same with the improved tank and 20 connections. By means of such tank the cooled water for the motor can be increased 25 to a substantial extent and a very convenient and serviceable device is provided, as for use with an automobile when it is found that the motor is likely to overheat, or more especially where, as is frequently 30 done, an automobile is converted into a truck or the like and the engine is subjected to an increased load and therefore requires additional cooling facilities and water supply.

The invention is, of course, applicable to engines having a water pump, as well as to engines of the type illustrated, and generally it will be understood that the invention is not limited to the construction shown for the purposes of illustration, and that changes and modifications may be made within the scope of my claims without departing from my invention.

I claim:

1. The combination with a water cooled motor and radiator, of an auxiliary water tank directly connected to and supported by the motor casting and adapted to be interposed in the water circulation system between the motor and the radiator with the water circulation outlet of the radiator leading into said tank and the water circulation inlet of the motor leading out of said tank.

2. An auxiliary tank for water cooled mo-

tors, and means for connecting said tank directly to the water inlet of the motor, said connecting means serving also as the entire supporting means for the tank.

3. An auxiliary water tank for water cooled motors adapted to be directly connected to the water inlet of the motor, the connecting means passing entirely through the tank, and a spacing member within the tank for taking the thrust of the connecting means.

4. In an auxiliary tank for water cooled motors, means extending entirely through the tank for directly connecting it to the water inlet of an internal combustion motor, a spacing member within the tank for taking the thrust of the connecting means, and a passage through said connecting means and the tank wall for affording communication between the interior of the tank and the water inlet of the motor.

5. In an auxiliary tank for water cooled motors, means extending entirely through the tank for connecting same to the water inlet of the motor, a spacing member within the tank for taking the thrust of the connecting means, and means for securing the tank walls to the connecting member.

6. In an auxiliary water tank for water cooled motors, an internal bracket extending from wall to wall of the tank, and means passing through said bracket for securing said tank directly to the motor.

7. In an auxiliary water tank for water cooled motors, a bracket extending from wall to wall of the tank and comprising a pair of posts and bores therein, and an intermediate opening for communicating with the water inlet, said bores being enlarged at their ends and the material of the tank walls extending into said enlarged portions, whereby the bracket is located and maintained in place, bolts extending through said bores and through the tank for securing the tank directly to the water inlet of the motor with the interior of the tank in communication with said water inlet, and means for connecting the tank at another point with the water outlet of a radiator.

In testimony that I claim the foregoing, I hereto set my hand, this 16th day of July, 1918.

CHARLES J. DALLEY.
